(57) **CLAIM**

The ornamental design for a vehicle, toy, and/or replicas thereof, as shown and described.

DESCRIPTION

This application contains subject matter related to the following co-pending U.S. design patent applications:

Application Ser. No. 29/347,797, filed herewith and entitled "Hood for a Vehicle";

Application Ser. No. 29/347,796, filed herewith and entitled "Rear Door for a Vehicle";

Application Ser. No. 29/347,795, filed herewith and entitled "Front Bumper for a Vehicle";

Application Ser. No. 29/347,793, filed herewith and entitled "Front Bumper for a Vehicle";

Application Ser. No. 29/347,794, filed herewith and entitled "Rear Bumper for a Vehicle";

Application Ser. No. 29/347,788, filed herewith and entitled "Rear Bumper for a Vehicle";

Application Ser. No. 29/347,789, filed herewith and entitled "Door for a Vehicle";

Application Ser. No. 29/347,790, filed herewith and entitled "Door for a Vehicle";

Application Ser. No. 29/347,791, filed herewith and entitled "Rear Fender for a Vehicle";

Application Ser. No. 29/347,792, filed herewith and entitled "Decorative Element for a Vehicle";

Application Ser. No. 29/347,800, filed herewith and entitled "Decorative Element for a Vehicle";

Application Ser. No. 29/347,799, filed herewith and entitled "Headlight for a Vehicle"; and

Application Ser. No. 29/347,798, filed herewith and entitled "Taillight for a Vehicle".

FIG. 1 is a left, front perspective view of a vehicle, toy, and/or replicas thereof according to my design, the right, front perspective view being mirror symmetrical;

FIG. 2 is a left, rear perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

The broken lines are for illustrative purposes only and form no part of the claimed design.
